UNITED STATES PATENT OFFICE.

LEANDER PELTON, OF DES MOINES, IOWA.

BROOM-SEWING MACHINE.

1,175,290.

Specification of Letters Patent.

Patented Mar. 14, 1916.

Application filed December 4, 1911. Serial No. 663,842.

To all whom it may concern:

Be it known that I, LEANDER PELTON, a citizen of the United States, residing at Des Moines, in the county of Polk and State of Iowa, have invented a certain new and useful Broom-Sewing Machine, of which the following is a specification.

In the art of broom sewing it has been customary heretofore to provide a broom clamp in which a broom may be supported and automatically moved past the point where reciprocating needles perform the sewing. Before moving the broom clamp to position where the needles engage the broom it is necessary for the operator to wrap the thread around the broom and also to readjust the broom within the clamp; then when this has been done the broom clamp is moved to position in the path of the needles and the operator must wait until the broom has passed beyond the needles before he can apply another thread and readjust the broom in the clamp.

The object of my present invention is to provide simple, durable and inexpensive means whereby an operator may cause the machine to sew a greatly increased number of brooms in a given period.

More specifically it is my object to provide a single broom sewing mechanism and a number of broom clamping devices so arranged that during the time that one of the broom clamping devices is passing through between the needles the other is in position where an operator may place a broom in it and pass the thread around the broom so that there is always one broom clamp in position where the operator may prepare a broom to pass between the needles and another broom clamp in position between the needles so that the entire time of an operator may be occupied and no time need be lost by the operator in waiting for the needles to perform their function.

More specifically it is my object to provide means whereby the broom clamps are automatically returned to position accessible to the operator after they have passed between the needles; and also to provide means for automatically bringing the broom clamps to position for moving between the needles.

A further object is to provide means for automatically closing and holding the broom clamping jaws during the time that

they are passing through between the needles.

My invention consists in the construction, arrangement and combination of the various parts of the device, whereby the objects contemplated are attained, as hereinafter more fully set forth, pointed out in my claims and illustrated in the accompanying drawings, in which:

Figure 1 shows a front elevation of a broom sewing machine embodying my invention with brooms in the broom clamps. Fig. 2 shows a side elevation of same. Fig. 3 shows a top or plan view of same, and Fig. 4 shows an enlarged, detail, sectional view of portions of the broom clamping jaws and the vertical adjustable broom holder within the jaws.

Referring to the accompanying drawings, I have used the reference numeral 10 to indicate the machine frame provided with a main power shaft 11 that may be driven by a pulley 12 thereon. Mounted on top of the frame are two rock shafts 13, each of which is provided with a downwardly extended needle frame 14 having a needle 15 at its lower end. I have provided for rocking the shafts 13 and thus reciprocating the needles by means of crank arms 16 in the shaft 11, each of which crank arms is connected by means of a rod 17 with an arm 18 on the shaft 13. This needle operating mechanism of itself forms no part of my present invention.

Arranged near the bottom of the frame 10 is a stationary shaft 19 having two collars 90 rotatably mounted thereon. On each of these collars is a broom clamping standard 21 pivotally supported to swing in a plane parallel with the shaft 19 so that each of said standards 21 is capable of universal movement relative to the stationary shaft 19. At the upper end of the standard 21 is a stationary clamping member 22 and a pivoted clamping member 23. Arranged within each broom clamp is a broom holder 24, illustrated in Fig. 4, and having a downwardly extended arm 25 which is pivoted at its lower end to a lever 26, the free end of which lever is capable of up and down movement. Pivoted to the front of the standard, adjacent to the end of said lever, is a notched arm 27 yielding held by a spring 28 to position in engagement with the lever 26 so

that the lever may be yieldingly held by the arm 27 in any one of the notches on said arm in which the lever may be placed. By this means the broom holder may be vertically adjusted within the broom clamp when the sides of the broom clamp are not firmly held together. The particular construction of the broom holder and its adjusting means is not important and any of the ordinary forms of this device may be used.

To provide for automatically clamping a broom between the clamping jaws and for advancing the broom clamp through between the needles, I have provided the following mechanism: Arranged on one side of the broom clamp, I have provided two rollers 29 designed to engage one of the clamping jaws when said jaw passes between the needles. On the opposite jaw, I have provided on its outer face a rack 30 designed to be engaged by two pinions 31 and 32, which pinions are both in mesh with an intermediate idler pinion 33 which causes both of the pinions 31 and 32 to turn in the same direction. To provide means for moving said pinions, I have mounted the pinion 32 on an upright shaft 34 having at its upper end a ratchet wheel 35. This ratchet wheel is driven by means of a cam 36 on the power shaft 11, which cam is arranged to engage an arm 37 fixed to an upright rock shaft 38. This rock shaft has at its upper end an arm 39 having a link 40 pivoted to it, and said link in turn is pivoted to an arm 41, which arm is rotatably mounted on the upright shaft 34 and is provided with a pawl 42 designed to engage the ratchet wheel 35. A pawl 43 is also mounted on the frame of the machine to engage the ratchet wheel 35. By this means, it is obvious that the broom clamps will be moved through between the needles at a speed proportionate to the speed at which the needles are moved and the said pinions 31 and 32 are so spaced relative to the rollers 29 that when a broom clamp passes between the pinions on one side and the rollers on the other the jaws thereof will be firmly held together to grasp the broom.

I preferably provide a curved portion 30^a on the inner end of the rack 30 that will first engage the pinion 31 and move the jaws together.

In order to provide for returning the broom clamps to starting position after they have passed between the needles, I employ the following: Immediately in the rear of the position that a broom clamp occupies after passing through between the needles is a forwardly extended track member 44. This track member has two inclined faces, one extending rearwardly and toward the left and the other rearwardly and toward the right, each of which is connected to a substantially semicircular track member 45,

which track members both incline downwardly and to the front of the machine. One of the broom clamps is intended after passing between the needles to move first to the left and then forwardly, and in order to accomplish this purpose the standards 21 are each provided with an offset portion at 46, as shown in Fig. 1, one offset portion being inclined to the right and the other to the left. Hence when that particular broom clamp, shown at the center of Fig. 1, passes between the needles the standard 21 will engage the left side of the inclined track member 44 and be directed toward the left while the other broom clamp will strike the portion of the track 44 that inclines toward the right and it will be moved first to the right and then forwardly. The object of having the track inclined, as shown, is to cause the broom clamps to automatically, by gravity, return to their forwardly inclined positions as soon as they have passed beyond the point where the pinion 32 engages the rack 30.

For the purpose of automatically engaging each broom clamp when at its forwardly inclined position and moving it toward the pinions 31, I have fixed to the stationary member of each broom clamp a hooked arm 47 projected forwardly from the broom clamp and of such size and shape that the hooked arm on one broom clamp will pass forwardly around the other broom clamp when the latter is in its forwardly inclined position and then as the first mentioned broom clamp moves between the needles the second will be moved by said hooked arm to position for entering between the needles.

In practical operation and assuming that the parts are in the positions shown in Fig. 2, and that the machine is being operated, then the broom that is in position adjacent to the needles will be firmly clamped and will be advanced between the needles automatically. During this time the other or forwardly inclined broom clamp will have its jaws relaxed so that the operator may readjust the broom holder between said jaws and the operator will also have an opportunity to place the thread around the broom so that as soon as the first broom has been sewed the second broom will be in proper condition to enter between the needles. Then the first mentioned broom clamp automatically returns to a forwardly inclined position and the operator may have an opportunity to readjust the broom and to place a thread thereon while the second broom is being sewed.

A certain amount of time is necessary to enable the operator to readjust a broom within the clamp and also to place a thread around it preparatory to sewing and in machines where only a single broom clamp is employed the sewing mechanism is unnecessarily idle during the time that the operator

is manipulating the broom within the clamp and placing a thread around it. By means of my improvement the sewing operation may be substantially continuous for the reason that by having two clamps one of them may be moving through between the needles while the operator is readjusting and placing the thread around the other so that both the operator and the machine may be substantially continuously employed.

By providing a series of broom clamps that are capable of being moved continuously in one direction past the needle operating mechanism and by having these broom clamps capable of independent movement toward and from each other, I accomplish a very desirable result in that while the needles are engaged in the operation of sewing the broom that is in one of the clamps and is necessarily advancing slowly, the other clamp may return rapidly to position accessible to the operator and the operator may then pass a twine around a broom in said latter clamp, and then the latter broom clamp may be moved to position adjacent to the former and before the operation of sewing is completed on the broom in the first clamp, so that, when the broom in the first clamp is completely sewed the needle operating mechanism will at once engage the broom in the second clamp without loss of time and without stopping the broom sewing mechanism so that the broom sewing mechanism may operate continuously and the operator may put in his time continuously in applying twine to the various brooms and in readjusting them within the clamps. Obviously if a series of broom clamps are provided that are spaced apart from each other and not capable of movement toward each other, then a great deal of time is wasted during the time that the needles cease operation on one broom and before they begin operation on the next, and if, on the other hand, a series of broom clamps are provided in which the brooms are not properly spaced apart at any time then the operator could not conveniently and easily apply the twine to one of the brooms while the other was being operated upon by the needles.

The rollers that engage the sides of the broom clamp may either be smooth or toothed as desired and in the accompanying claims where the term "rollers" is employed in describing these elements, I intend the term to cover either smooth or toothed rollers.

In order to successfully accomplish the purposes for which my improved sewing machine is intended, it is essential that the broom clamps be advanced past the sewing mechanism at a relatively slow speed, and that they then be returned to the starting point at a relatively fast speed so that only a few broom clamps need be employed and

the operation of sewing may be carried on continuously otherwise there would have to be a large number of unnecessary broom clamps or the operation of sewing would at times be delayed.

I claim as my invention:

1. In a machine of the class described, the combination of a frame, needle operating mechanism, a number of broom clamps, means for slowly moving a broom clamp through a path of travel in operative relationship to the needle operating mechanism, and means for rapidly returning a broom clamp through a different path to position for reentering operative relationship to the needle operating mechanism.

2. In a machine of the class described, the combination of a frame, needle operating mechanism, a number of broom clamps, means for slowly moving a broom clamp past the needle operating mechanism, and means for rapidly returning a broom clamp to position for reentering operative relationship to the needle operating, said broom clamps being capable of movement toward and from each other.

3. In a machine of the class described, the combination of a frame, needle operating mechanism, a number of broom clamps each capable of movement in a single path past the operative points of the needle operating mechanism and in separate paths for returning at comparatively high speed to position to start sewing, and means operated from the needle operating mechanism for moving the broom clamps through said single path in operative position relative to the needle operating mechanism at comparatively slow speed.

4. In a machine of the class described, the combination of a frame, needle operating mechanism, a number of broom clamps, means for slowly moving a broom clamp past the needle operating mechanism, and means for rapidly returning a broom clamp to position for reentering operative relationship to the needle operating, each of said broom clamps being provided with independent jaws whereby each clamp may be opened or closed independently of the other broom clamps.

5. In a machine of the class described, the combination of a frame, needle operating mechanism, a number of broom clamps, each having its own independent clamp jaws, and means on the frame adjacent to the needle operating mechanism for pressing the jaws together and advancing them past the needle operating mechanism.

6. In a machine of the class described, the combination of a frame, needle operating mechanism, two broom clamps each mounted for movement independently of the other, means for advancing a broom clamp past the needle operating mechanism at slow

speed, and means for returning a broom clamp at high speed to position for reëntering operative relation to the needle operating mechanism, whereby the operation of sewing may be carried on substantially continuously.

7. In a device of the class described, the combination of a frame, needle operating mechanism, two broom clamps, means for 10 moving them past the needle operating mechanism, and a track device designed to be engaged by said broom clamps after they have passed beyond the needle operating mechanism and to cause the broom clamps 15 to return by gravity to position for reëntering the needle operating mechanism.

8. In a device of the class described, the combination of a frame, needle operating mechanism, two broom clamps, means for 20 moving them past the needle operating mechanism, and a track device designed to be engaged by said broom clamps after they have passed beyond the needle operating mechanism and to cause the broom clamps 25 to return by gravity to position for reëntering the needle operating mechanism, said broom clamps and said track being so shaped and arranged that one broom clamp will move first to the left and then forwardly 30 and the other first to the right and then forwardly.

9. In a machine of the class described, the combination of a frame, needle operating mechanism, two broom clamps, each 35 being universally pivoted at its lower end, and a track device comprising a track member designed to be engaged by the broom clamps after they have passed beyond the needle operating mechanism, said track 40 member having rearwardly and laterally inclined portions extending in opposite directions, and another track member on each side of the frame substantially semicircular in shape and extended from the rear to the 45 front of the machine and inclined downwardly toward the front, one of said broom clamps being so shaped as to engage one side of the track member at the rear and the other being so shaped as to engage the 50 other side of the track member at the rear.

10. In a machine of the class described, the combination of a frame, needle operating mechanism, two broom clamps, each 55 being universally pivoted at its lower end, and a track device comprising a track member designed to be engaged by the broom clamps after they have passed beyond the needle operating mechanism, said track 60 member having rearwardly and laterally inclined portions extending in opposite directions and another track member on each side of the frame substantially semicircular in shape and extended from the rear to the front of the machine and inclined downwardly toward the front, one of said broom 65

clamps being so shaped as to engage one side of the track member at the rear and the other being so shaped as to engage the other side of the track member at the rear, and a hooked arm on each broom clamp extended forwardly, the hooked arm on one broom clamp being designed to engage the other broom clamp when the latter broom clamp first reaches its forward limit of movement.

11. In a machine of the class described, 75 the combination of a frame, a broom clamp having two jaws, one of which is movable toward and from the other, a rack carried by said movable jaw, and a pinion carried by the frame to engage said rack and to 80 force the movable jaw toward the other one and also to advance the broom clamp.

12. In a machine of the class described, the combination of a frame, a broom clamp having two jaws, one of which is movable 85 toward and from the other, a rack carried by said movable jaw, and a pinion carried by the frame to engage said rack and to force the movable jaw toward the other one and also to advance the broom clamp, 90 the end of said rack that first engages the pinion being curved, for the purposes stated.

13. In a machine of the class described, the combination of a frame, a broom clamp having one jaw capable of movement toward and from the other, a roller mounted in the frame on one side of the path of the broom clamp designed to engage one of the jaws, a rack mounted on the other jaw, 95 and a pinion mounted on the frame to engage said rack for clamping the jaws between said pinion and said roller.

14. In a machine of the class described, the combination of a frame, a power shaft, 105 needle operating mechanism connected with the power shaft, a pinion operatively connected with the power shaft, a second pinion rotatably supported, and an intermediate pinion in mesh with both to operate the second pinion in unison with the first and in the same direction, a broom clamp, and a rack carried by the broom clamp and designed to be engaged by both said first and second mentioned pinions.

15. In a machine of the class described, the combination of a frame, a power shaft, needle operating mechanism connected with the power shaft, a pinion operatively connected with the power shaft, a second pinion 120 rotatably supported, and an intermediate pinion in mesh with both to operate the second pinion in unison with the first and in the same direction, a broom clamp, a rack carried by the broom clamp and designed to be engaged by both said first and second mentioned pinions, and two rollers 125 designed to engage the opposite side of the broom clamp when in position adjacent to said pinions.

16. In a machine of the class described, 130

the combination of a frame, a broom clamp having its lower end universally pivoted, said clamp having two jaws, one being capable of movement toward the other, and
5 means for forcing said jaws toward each other and also for advancing the jaws, and also for holding the broom clamp against lateral movement, said means comprising a rack on one of the jaws, a roller on one
10 side of the path of the broom clamp to engage the jaw opposite from the rack, and a pinion to engage said rack.

17. In a machine of the class described, the combination of a frame, needle operating mechanism, a broom clamp capable of
15

being moved past the needle operating mechanism, rollers on opposite sides of the broom clamp and adjacent to the needle operating mechanism, and means for driving the rollers, said parts being so arranged 20 that when the broom clamp is engaged by the rollers the sides of the broom clamp will be pressed together to engage a broom therein, and the broom clamp will be moved past the needle operating mechanism.
